DESIGN FOR A BILLFOLD

Samuel Smallman, New York, N. Y.

Application May 20, 1938, Serial No. 77,291

Term of patent 3½ years

To all whom it may concern:

Be it known that I, Samuel Smallman, a citizen of the United States of America, residing in the city of New York, county of New York, and State of New York, have invented a new, original, and ornamental Design for a Billfold, of which the following is a specification, reference being had to the accompanying drawing forming part thereof.

The figure on the drawing is a plan view of a billfold showing my new design.

The back of the billfold is substantially plain.

I claim:

The ornamental design for a billfold, substantially as shown and described.

SAMUEL SMALLMAN.
